UNITED STATES PATENT OFFICE.

RICHARD S. BRYANT, DECEASED, LATE OF CLEVELAND, OHIO, BY OTTO H. JOBSKI,
SPECIAL ADMINISTRATOR, OF CLEVELAND, OHIO, ASSIGNOR TO THE STANDARD
PARTS COMPANY, OF CLEVELAND, OHIO, A CORPORATION OF OHIO.

MANUFACTURE OF RIMS.

1,260,315.

Specification of Letters Patent. Patented Mar. 26, 1918.

Application filed May 10, 1917. Serial No. 167,686.

To all whom it may concern:

Be it known that I, Otto H. Jobski, a citizen of the United States, and a resident of Cleveland, county of Cuyahoga, and State of Ohio, administrator of the estate of

5 RICHARD S. BRYANT, late a citizen of the United States and resident of Cleveland, Ohio, deceased, believe said RICHARD S. BRYANT to have invented a new and useful
10 Improvement in the Manufacture of Rims, of which the following is a specification, the principle of the invention being herein explained and the best mode in which it was contemplated applying said principle, so as
15 to distinguish it from other inventions.

The present improvements relate more particularly to the manufacture of tire-supporting rims for vehicle wheels, which rims are transversely split at one point in 20 their circumference, in order to facilitate the removal and replacement of tires thereon. Prior to the present invention, rims of this sort have first been made in the same fashion as so-called integral or 25 continuous rims, viz., a strip of stock of the correct length has been circled, the ends have been brought into abutting relation and welded together, and the flat band or annulus thus formed has thereupon been appropriately flanged for the reception of 30 either straight side or clincher tires as desired. Following the completion, in this fashion, of the continuous or integral rim, such rim has been literally split, that is 35 sawed in two at a selected point in its circumference.

The object of the present invention is to 40 avoid this roundabout method of manufacture by eliminating the necessity for welding the rim blank or preliminarily circled strip of stock, so that the finished product may be secured with a minimum number of operations and a corresponding lowering of the cost of manufacture. To the 45 accomplishment of this and related ends, the invention, then, consists of the steps hereinafter fully described and particularly pointed out in the claims.

The annexed drawing and the following 50 description set forth in detail one approved

method of carrying out the invention, such disclosed mode, however, constituting but one of the various ways in which the principle of the invention may be used.

In said annexed drawing:— 55

Figure 1 represents an end view, and Fig. 2 a side elevation of a strip of stock such as is used in the manufacture of rims of the sort in hand; Fig. 3 represents the flanging operation which preferably constitutes the 60 first step in my present improved process or method of manufacture; Fig. 4 is a side elevation of the strip of stock after being thus flanged; Fig. 5 illustrates the circling operation; Fig. 6 represents the trimming 65 operation; and Fig. 7 represents the final setting and sizing step.

In proceeding to make a transversely split rim according to the present improved process or method, the blank strip A, as 70 shown in Figs. 1 and 2, is passed through between suitable rolls 1, 2, to laterally flange such strip, as illustrated in Fig. 3, the flanges a formed thereon being suitable either for engagement with a straight side 75 tire, as in the figure just referred to, or for a clincher tire, as desired. Preferably the strip is cut up into sections having a length slightly in excess of the circumference of the desired rim before being thus flanged; 80 but this is a matter of indifference since a strip of indefinite length may be run through the flanging rolls and cut up into sections afterward, or for that matter such sections may be cut off incidentally to the circling operation which constitutes the next step in the 85 process.

As illustrated in Fig. 5, the circling is accomplished by means of rolls in a fashion 90 more or less familiar. In other words, feed rolls 3 pass the stock in between two positively driven rolls 4, fixed rolls 5 being so located with reference to the latter as to bend such stock into approximately circular form. Where, as indicated is the preferred 95 practice, the stock is previously cut up into sections of the desired length, each such section will be rolled up into a circle so as to constitute what may be called a rim blank. Where the stock has not been previously 100

cut up into sections it will be thus cut off upon the completion of successive circles. The circumference of the blank, in any event, will be a trifle in excess of the pre-scribed circumference of the finished rim.

- 5 The next step in the general process is to place such preliminarily formed rim or rim blank on a circular mandrel 6 having an external diameter approximately equal to the 10 internal diameter of the blank, so that in other words the latter may be drawn (by means of a flexible band 7 for example) into close fitting contact with the mandrel without its ends contacting. The latter, however, 15 overlie a slot 8 in the mandrel through which a shearing blade 9 is adapted to pass, this slot and the path of the blade being disposed at whatever angle with respect to a radius of the mandrel passing through the 20 point in question may be desired. Since ordinarily in rims of the type in question the slit is desirably inclined at an angle to the radius of the rim passing through the point of such split, this slot 8 and blade 9 25 are correspondingly inclined with reference to the radius of the mandrel.

With a rim placed on the mandrel in the fashion described, by operating the shearing blade 9, both ends of such rim will be simultaneously 30 cut off at the angle indicated, and by having the distance around the mandrel from one edge of the slot 8 to the other of exactly the circumference of the finished rim, it will be seen that, following such trimming operation, the blank will be left of 35 just the proper length, when its ends are brought into abutting relation.

The last step in the process consists in setting and sizing the rim, which may be 40 done in a tire setting machine of familiar construction (see Fig. 7). In other words, the rim blank is placed on a mandrel 10 having an external diameter the same as the internal diameter of the finished rim, and a 45 series of segmental dies 11 are then forced radially inwardly, as by hydraulic pressure, to give such blank a true circular form, and at the same time bring its ends into proper abutting relation. In order to prevent a 50 ring of the ends as well as to allow for a slight clearance between them, such as is desirable, a thin blade 12, carried by one of the die members 11 of the machine, may be interposed as indicated in the figure last 55 referred to. This blade, as a matter of fact, may be thicker than the desired clearance, inasmuch as the fatigue in the metal will take up a portion of the space represented thereby, when the rim is removed from the 60 machine.

The valve-stem hole, as well as the holes and recesses at the respective ends of the rim for the attachment of the locking de-

vice, where one is used, may be formed in 65 connection with one of the foregoing described steps, but will preferably be made by placing the rim in a suitable punch press (not shown) having properly formed dies, after the blank, so-called, has been thus 70 made into an otherwise finished rim. The formation of such valve-stem hole, etc., of course forms no part of the present invention.

The foregoing series of operations renders 75 it possible to make a finished rim out of a straight strip of stock without any intermediate welding operation being required, and thus materially lowers the cost of manufacture, as has been ascertained in actual 80 practice. A superior product is also formed, since there is no welded joint in the finished rim, and by shearing off the ends, which are subsequently to abut in the finished rim, not only are such ends maintained smooth, but 85 they are given exactly the proper angularity to insure a close joint when they are brought into abutting relation.

Other modes of applying the principle of my invention may be employed instead of 90 the one explained, change being made as regards the method herein disclosed, provided the step or steps stated by any one of the following claims or the equivalent of such stated step or steps be employed.

I therefore particularly point out and distinctly claim as the invention:—

1. In the manufacture of transversely split tire-supporting rims for vehicle wheels, the steps which consist in flanging and circling a strip of stock having a length slightly in excess of the circumference of the desired rim; trimming off the ends of such circled strip to leave the latter of the correct length; and then setting the same to bring the ends 105 into contact, substantially as described.

2. In the manufacture of transversely split tire-supporting rims for vehicle wheels, the steps which consist in flanging and circling a strip of stock having a length slightly 110 in excess of the circumference of the desired rim; trimming off the ends of such circled strip to leave the latter of the correct length; and then setting and shaping the same to bring the ends into contact and fix the rim 115 in a true circle.

3. In the manufacture of transversely split tire-supporting rims for vehicle wheels, the steps which consist in flanging and circling a strip of stock having a length slightly 120 in excess of the circumference of the desired rim; simultaneously trimming off both ends of such circled strip at the same angle and so as to leave the strip of the correct length; and then setting the same to bring the ends 125 into contact, substantially as described.

4. In the manufacture of transversely

split tire-supporting rims for vehicle wheels, the steps which consist in flanging and circling a strip of stock having a length slightly in excess of the circumference of the desired 5. rim; simultaneously trimming off both ends of such circled strip at the same angle, namely, an angle inclined to a radius of said strip, and thereby leaving the latter of the correct length; and then setting the

same to bring the ends into contact, substantially as described.

10

Signed by me, this 7th day of May, 1917.
OTTO H. JOBSKI,
Administrator of the estate of Richard S.

Bryant, deceased.
